FLUSH TANK VALVE

Arthur N. Asselin, Fall River, Mass.

Application October 7, 1941, Serial No. 414,010

4 Claims. (Cl. 137—104)

This invention relates to a flush tank valve of the ball cock type described in my copending application filed April 7, 1941, Serial No. 387,354.

An object of the present invention is to provide a combined opening and closing device which will eliminate noise as the valve is closed by the flush tank float.

A further object is to provide a vacuum breaker for a flush tank valve adapted to prevent the suction of the water out of the flush tank by 10 vacuum created when the supply of water is shut off in the supply pipe.

A further object is to provide apparatus of this character which will be formed of a few strong, simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming a part of this specification:

Figure 1 is a longitudinal sectional view of a flush tank valve constructed in accordance with the invention, shown in full lines fully closed, 30 and in dotted lines showing the plunger valve in position to register the air inlet openings with the openings in the wall of the valve bearing so that atmospheric air may break the vacuum action and prevent water being sucked out of the 35 flush tank when the water supply is cut off.

Figure 2 is a longitudinal sectional view of the valve shown fully open.

Figure 3 is an end elevation of the flush tank valve looking from the direction of the float.

Figure 4 is a longitudinal sectional view of the flush tank valve showing the coating cam projections on the silencing lever and valve operating lever a few seconds before the float rises sufficiently to close the valve.

Figure 5 is a longitudinal sectional view similar to Figure 4 but showing the silencing lever and valve operating lever in position to provide a small gap between the valve and its seat momentarily as the valve is being completely closed so that water hammering will be prevented.

Figure 6 is a detail perspective view of the plunger valve.

Figure 7 is a longitudinal sectional view of a modified form of the invention in which a plug 55

is equipped with a vacuum valve adapted to be screwed into the supply pipe instead of being built into the plunger valve.

Referring now to the drawing in which like characters of reference designate similar parts in the various views, 10 designates a flush tank valve body, the same having a water inlet nozzle 11, adapted to receive a supply pipe 12 for filling the flush tank. The body is provided with a longitudinal bore 13 having a nipple 14 to receive a siphoning tube 15, and diametrically opposite the nipple the body is provided with a nipple 16 which communicates with the bore and receives the filling pipe 17 for the tank. A tubular valve cage 18 is removably mounted in the bore and is provided with openings 19 which establish communication between the bore of the cage and the bore of the valve body so that water may exit through the siphoning tube 15 and the filling pipe 17. A washer nut 20 is threaded into the bore of the body and confines the cage in place.

A plunger valve 21 is mounted in the bore of the cage and projects through the washer 20. The plunger valve is cylindrical and hollow, see 25 Figure 6, and is provided with air inlet openings 22 the purpose of which will presently be explained. The plunger valve is provided with a stem 23 of reduced diameter which extends through the bore of the cage and is provided with a disk valve 24 having a beveled portion 25 adapted to seat against a beveled valve seat 26 formed on the valve cage.

When the plunger valve is fully closed as shown in Figure 1, and also when the plunger valve is fully open as shown in Figure 2, the aforesaid inlet openings 22 are masked by the wall of the bore of the cage 18. However, when the water supply is cut off from the supply pipe 12 with resultant suction being created in the nozzle 11 the plunger valve will be moved forwardly to the dotted line position shown in Figure 1 at which time it seals a water inlet opening 27 and is stopped against further movement by the dia- 40 phragm 28 in which the opening is formed. At this time the air inlet openings 22, of which preferably there are four, will be moved into registration with the openings 19 in the cage so that atmospheric air may equalize through the hollow plunger valve and tube 15 and pipe 17 to break the vacuum action which would otherwise exist to suck the water out of the flush tank when the water supply is cut off from the nozzle 11 and water supply pipe 12.

The opening and closing device for promoting

noiseless operation of the plunger valve comprises a valve operating lever 29 which is pivoted on a pivot pin 30 on the valve body at a point above the projecting end of the plunger valve 21. The valve operating lever is provided with a downwardly directed arm 31 which contacts with the projecting end of the plunger valve, and is also provided with an outwardly directed arm 32 against the upper side of which the float lever 33 contacts. The valve operating lever and the float lever are mounted on the same pivot pin 30 for movement together or for movement relative to each other.

A latch lever 34, which may be called the silencing lever, is pivoted at one end on a pivot pin 35 carried by ears 5 disposed on the valve body at a point higher than, and inwardly of, the pivot pin 30 of the valve operating lever and the float lever. The latch is provided on the underneath side with a cam projection 36 and is also provided on the same side as the projection with a downwardly extending finger 37 adapted to be engaged by the float lever 33.

The valve operating lever 29 is provided with an upwardly extending projection 38 which contacts with the downwardly extending projections 36 of the latch lever in such manner that the float lever will, during its upward movement, move the projection 36 of the latch lever out of engagement with the projection 38 of the valve operating lever, see Figures 2 and 5, the movement being so timed that a small gap 39 will exist between the valve 24 and the valve set 26 for an instant before the float permits the valve to fully close under water pressure thereagainst, and this gap has been found in practise to positively eliminate the noise or hammering hitherto existing just as the valve is moved to completely closed position.

As best shown in Figure 7 instead of incorporating the vacuum breaking openings in the plunger valve itself a hollow plug 40 may be threaded into an extension 41 on the water inlet nozzle 42. A hollow plunger valve 43 is mounted to slide endwise in the bore of the hollow plug and is provided on the inner side with a valve 43, adapted to seat on a beveled seat 44 at one end of the bore of the plug. A nut 45 is threaded onto the other end of the plunger valve and is adapted to engage a stop shoulder 46 on the adjacent end of the plug to limit opening movement of the valve 43 under vacuum suction thereagainst when the water is cut off from the supply nozzle 42. The nut 45 and the plunger valve 43 are provided with respective air supply openings 47 and 48 which permit atmospheric air to rush through the bore of the hollow plunger valve and break the vacuum which would tend to suck out the water from the flush tank when the water supply is cut off from the nozzle 42.

Since the operation of the parts has been described as the description of the parts progressed it is thought the invention will be fully understood without further explanation.

What is claimed is:

1. An opening and closing device for flush tank valves comprising a valve housing, a valve therein, a valve operating lever pivoted on the housing at a point upon the outer end thereof, said valve operating lever being provided with a downwardly directed arm engaging the outer end of the valve, the valve operating lever being also provided with an outwardly directed arm, a float

having a stem engaging the outwardly directed arm, means pivotally mounting the float stem and the valve operating lever for movement together and for movement relatively to each other on the housing, a latch lever pivoted at one end on the housing at a point higher than and inwardly of the pivot of the valve operating lever and the float stem, a projection extending downwardly from the latch lever, an upwardly extending projection on the valve operating lever, and a downwardly extending finger on the free end of the latch lever adapted to establish such connection between the latch lever and the float stem that the float stem will, during its upward movement, move the projection of the latch lever out of engagement with the projection of the valve operating lever to momentarily provide a small gap between the valve and its seat for eliminating water hammering as the valve moves to fully closed position.

2. An opening and closing device for flush tank valves, comprising a valve housing, a valve therein, a valve operating lever pivoted on the housing at a point above the outer end of the valve, a downwardly extending arm carried by the lever and engaging the outer end of the valve, a float lever pivoted on the pivot of the valve operating lever, a latch lever pivoted to the housing above the valve operating lever and adapted to lock the valve operating lever, and an arm carried by the latch lever and engaging the float lever, whereby the valve operating lever is released by the upward movement of the float lever.

3. An opening and closing device for flush tank valves, comprising a valve housing, a valve therein and extending beyond the housing, a valve operating lever pivoted on the housing at a point above the outer end of the valve, a downwardly extending arm carried by the lever and engaging the outer end of the valve, a float lever pivoted on the pivot of the valve operating lever, an upwardly extending arm carried by the valve operating lever, a latch lever pivoted to the housing above the valve operating lever and adapted to engage the upwardly extending arm of the valve operating lever and lock the same against movement, an arm carried by the valve operating lever and engaging the lower face of the float lever, and means carried by the latch lever for engaging the upper face of the float lever.

4. An opening and closing device for flush tank valves, comprising a valve housing, a valve therein and extending beyond the housing, a valve operating lever pivoted on the housing at a point above the outer end of the valve, a downwardly extending arm carried by the lever and engaging the outer end of the valve, a float lever pivoted on the pivot of the valve operating lever, an upwardly extending arm carried by the valve operating lever, a latch lever pivoted to the housing above the valve operating lever and adapted to engage the upwardly extending arm carried thereby and lock the same with the valve closed, an arm carried by the valve operating lever and engaging the lower face of the float lever, and a downwardly extending arm carried by the latch lever and engaging the upper face of the float lever, whereby the latch member is raised by the upward movement of the float lever to release the valve operating lever to allow the valve to close at a predetermined point of the upward movement of the float lever.

ARTHUR N. ASSELIN.
